UNITED STATES PATENT OFFICE.

WILLIAM B. DURGIN, OF CONCORD, NEW HAMPSHIRE.

DESIGN FOR A HANDLE FOR SPOONS, &c.

SPECIFICATION forming part of Design No. 20,542, dated March 3, 1891.

Application filed January 29, 1891. Serial No. 379,579. Term of patent 7 years.

To all whom it may concern:

Be it known that I, WILLIAM B. DURGIN, a citizen of the United States, residing at Concord, in the county of Merrimac and State 5 of New Hampshire, have invented and produced a new and original Design for the Handles of Spoons and other Flat Ware, of which the following is a specification, reference being had to the accompanying drawing, in which the figure represents a face view of a spoon having my new design produced on the handle thereof.

The leading feature of my design consists in the representation of a rock-like figure having the form of a human head and neck in profile.

The letter *a* indicates the said leading fea-

ture, in connection with which the minor features of the design are arranged, *b* indicating the representation of the moon as appearing among cloud effects and in the background, and *c* indicating the representation of a water-fall, the latter appearing in the foreground and merging into the plain surface of the handle of the spoon in the direction of the bowl 25 thereof.

I claim—

The design herein shown and described for the handle of spoons and similar flat ware.

WILLIAM B. DURGIN.
